(57) **CLAIM**

The ornamental design for a water and beverage making bottle, as shown and described.

DESCRIPTION

FIG. 1 is a front elevational view of a water and beverage making bottle showing my new design;

FIG. 2 is an enlarged top plan view thereof;

FIG. 3 is an enlarged front elevational view thereof with the lid in an alternative position;

FIG. 4 is an enlarged top plan view of FIG. 3;

FIG. 5 is an enlarged front elevational view thereof with the lid removed for clarity of disclosure;

FIG. 6 is an enlarged top plan view of FIG. 5;

FIG. 7 is an enlarged front elevational view thereof with the lid and base sleeve removed for clarity of disclosure;

FIG. 8 is an enlarged top plan view of FIG. 7;

FIG. 9 is an enlarged front elevational view of the lid portion shown separately for clarity of disclosure;

FIG. 10 is an enlarged top plan view of FIG. 9;

FIG. 11 is an enlarged front elevational view of the base sleeve shown separately for clarity of disclosure;

FIG. 12 is an enlarged top plan view of FIG. 11;

FIG. 13 is an enlarged front elevational view of the filter basket portion shown separately for clarity of disclosure;

FIG. 14 is an enlarged top plan view of FIG. 13;

FIG. 15 is an enlarged front elevational view of the thermal bulb portion shown separately for clarity of disclosure;

FIG. 16 is an enlarged top plan view of FIG. 15;

FIG. 17 is an enlarged front elevational view of the strainer platform portion shown separately for clarity of disclosure;

FIG. 18 is an enlarged top plan view of FIG. 17;

FIG. 19 is an enlarged front elevational view of the top cap portion shown separately for clarity of disclosure;

FIG. 20 is an enlarged top plan view of FIG. 19; and,

FIG. 21 is a reduced exploded view thereof.
